(57) **CLAIM**

The ornamental design for a teether base, as shown and described.

DESCRIPTION

FIG. 1 is a top, front, right perspective view of a teether base showing our new design;

FIG. 2 is a top, rear, left perspective view thereof.

FIG. 3 is front view thereof.

FIG. 4 is a rear view thereof.

FIG. 5 is a top view thereof.

FIG. 6 is a right view thereof.

FIG. 7 is a bottom view thereof.

FIG. 8 is a left view thereof.

FIG. 9 is a top, front, right perspective reference view thereof, shown in a position of use with an exemplary teether top; and,

FIG. 10 is a top, rear, left perspective reference view thereof, shown in a position of use with the exemplary teether top. The broken lines in the drawings illustrate unclaimed subject matter and form no part of the claimed design.

1 Claim, 5 Drawing Sheets
